MEASURING PUMP WITH FLEXIBLE TUBING

Louis Joseph Henry, Paris, France

Application July 30, 1947, Serial No. 764,760
In France March 7, 1941Section 1, Public Law 690, August 8, 1946
Patent expires March 7, 1961

9 Claims. (Cl. 222—38)

1

The object of my present invention is to provide a pump more particularly though not exclusively adapted for medical use, said pump being essentially characterized by the use of flexible tubes of rubber or any equivalent and suitable material with which there are combined, firstly push-rods adapted to produce, at suitable times, the obstruction or throttling of a point of said tubes, and secondly, a plate adapted to flatten the tube between those throttling points, the movement of said push members and said plate being correlated in such a manner that the flexible tubing element which is thus subjected to the action of said members will behave as a suction or pressure pump barrel.

My pump makes it possible to inject a plurality of liquids, or liquids on one hand and any desired gases on the other hand, in variable amounts according to the desires of the operator. The volume of flow of each of said liquids or gases injected in this way is adjustable for each individual tube without it being required to vary the speed of the motor provided to drive the pump.

As a result of the above-disclosed features, the pump according to my invention, makes it possible, for instance, to transfuse within a given time 300 cc. of blood, and in the same lapse of time and simultaneously therewith inject 10 cc. of an anaesthetic, the apparatus in such case comprising two tubes. The products may be injected separately, that is they may be introduced into different points of the patient's body; both tubes could also be connected with a single hypodermic needle, the proportioning of the injected fluid then being effected within the single tube interconnecting both the above-mentioned tubes.

My apparatus may operate either as an artificial heart (the output of both tubes then being alternated, one of the tubes being caused to aspirate while the other one discharges), or aspiration and discharge may be effected simultaneously, in which case my apparatus may constitute a metering-mixing device in which both products being pumped are mixed in predetermined proportions through adjustment of both rates of flow and throughout the entire duration of the discharge period.

As will be apparent from the disclosure given hereinafter in greater detail, the adjustment of the rate of flow makes it possible to vary the latter in each tube and independently from the other tube, from zero up to a maximum value, such adjustment being operable both at rest and when the apparatus is in use.

2

Any important feature of my new device is that the liquids or gases being pumped do not enter into contact with any valve or the like means: they flow through simple rubber tubes which do not require any lubrication, as distinguished from alternating pumps, vaned pumps, gear pumps, and the like. In this manner any possibility of the products flowing in the apparatus mingling with foreign materials is positively precluded, this being of capital importance in medicinal applications.

Positioning and removal of the tubes may be effected with the greatest of ease without requiring the dismantling of any mechanical member. It thus becomes an easy matter to clean and sterilize the tubes whenever necessary or desirable.

My apparatus may be formed with any suitable number of tubes. Merely by way of example, 20 there is described hereinafter an apparatus comprising two tubes as diagrammatically shown in the accompanying drawing:

Fig. 1 is an elevational view of the apparatus assembly with parts broken away and in cross section on line I—I of Fig. 5.

Fig. 2 is a cross section on line II—II of Fig. 4 in its left-hand side and an end view of the pump proper in its right-hand side.

Fig. 3 is a side view of the same pump, one side of the base being broken away to show a detail.

Fig. 4 shows the same device partly in cross section on line IV—IV of Fig. 2.

Fig. 5 is in its upper part a section on line V—V of Fig. 4, and in its bottom part a section on line V—V' of the same figure.

Fig. 6 shows the position of the control cams controlling the obturating push-rods of one of the tubes at the start of the suction phase.

Fig. 7 shows the position of the control cams of the obturating push-rods of the other tube at the start of the delivery stroke.

Fig. 8 is an elevational view partly in section of the general cam assembly for both tubes.

Fig. 9 is a plan view partly in section of Fig. 8.

Figs. 10 and 11 show in end view and in side elevation respectively one of the supports of the tube abutment plate, said support at the same time serving for adjusting purposes.

Fig. 12 is an end view of the counter with which the apparatus is provided.

Figs. 13 and 14 respectively are a bottom plan view and an elevational view of said counter.

Figs. 15 and 16 are an elevational and a plan view respectively of a detail of the counter.

Fig. 17 is an end view of Fig. 14, and Fig. 18 represents a flow indicator.

As already stated above, the apparatus forming the subject matter of this invention may comprise any suitable number of flexible tubes forming pump barrels. Since the control mechanism is identical for all of the tubes of a given apparatus, the mechanism actuating only one of those tubes will be described for greater simplicity in the disclosure.

In the case of a device with two tubes as shown in the drawing there is provided a means for synchronizing the suction and delivery strokes or periods in each tube, or on the other hand for causing them to alternate, depending on particular requirements.

The device is supported on a base 1 which in turn serves as a support for a shaft 2 on which are secured cams 3, 4, 5, 6, (and 3', 4', 5', 6' for the other tube). The shaft 2 is driven in rotation at a constant rate from an electric motor accommodated under the apparatus within a casing 71 upon which the base 1 is secured. Particular features of the control means from said motor will be given hereinafter.

The cams 3, 4, 5, 6 are engaged by one end (which may be provided with a follower roller) of levers 7, 8, 9, 10 rigid with pins 11, 12, 13 and 14 which also support levers 7', 8', 9', 10' actuating push-rods or members 15, 16, 17 and 18 respectively.

The end push-rods 17 and 18 (see Fig. 5) are adapted to effect at the requisite moments throttling of the tubes 27. They serve the function of check-valves and are operated alternately, one of them pressing upon the tube to throttle it while the other one releases the tube to enable liquid or gas to flow freely therethrough.

The push-rods 17 and 18 are slidable in fixed guides and are maintained in engagement with their controlling levers 9' and 10' by springs 17' and 18' which at the same time are adapted to maintain the levers 9 and 10 pressed against the cams 5 and 6.

The push-rods 15 and 16 located between the push-rods 17 and 18 are effective to flatten the tube 27 in the length thereof included between the end push-rods, in order to effect the discharge of the liquid or gas contained in the tube. Said push-rods 15 and 16 are connected with a pressure-plate 19 along which they are movable, the connection between said push-rod and said plate being for instance effected through a dovetail assembly which may best be seen in Fig. 1. The push-rods 15 and 16 are actuated synchronously by the levers 7' and 8' which in turn are controlled from the related cams and the thus obtained displacement of the push-rods and the plate 19 towards the tube 27 causes said tube to be clamped between the plate 19 and a fixed abutment plate 28.

When the plate 19 has reached the end of its stroke or in other words when the discharge of a desired amount of liquid or gas has been effected by displacement of the plate 19, the latter is retracted by the action of a spring 24" acting through the medium of a link 25 and a lever 26 upon a rod 24 guided in a recess formed in the post 23 and formed with an aperture 24'. It will be easily understood that the action of the spring 24" also results in maintaining the levers 7 and 8 constantly applied against the cams 3 and 4 from which they are controlled.

The just described control device for the plate 19 is devised so as to permit of adjusting the

rate of flow through the tube 27, such adjustment being effected by varying the amplitude of stroke of the plate 19. For that purpose, as previously stated, the push-rods 15 and 16 are movable along the plate 19. It follows that said push-rods according to the position occupied by them relatively to the central rod 24, are engaged by a point of the levers 7 and 8 which is more or less distant from the fulcrum axis of said levers. Consequently, the stroke of the push-rods 15 and 16 (and therefore that of the plate 19 with which they are combined) is also modified.

For such adjustment, it is necessary that the push-rods 15 and 16 be displaced by strictly equal amounts. For that purpose the displacement of the push-rods is controlled by a screw 20 formed with threads of opposite pitch acting upon the guides 15' and 16' of the push-rods 15 and 16. By rotating the screw 20 by means of the knobs 21 and 21' a simultaneous displacement in opposite directions by equal amounts is obtained for the guides 15' and 16' and therefore the push-rods 15 and 16. Such movement being effected either in a direction to bring the push-rods closer to the pivotal axis of the levers 7' and 8' or to space said push-rods further away from said axis.

The screw 20 is rotated in the walls 22 and 22' of the apparatus and is moreover supported in the central post 23. It may be provided with blocking means to set it in a required position.

The screw 20 could be replaced by a rapid adjustment device formed by a pinion rotating on the member 23 and meshing with sets of rack teeth one of which is rigid with the guide 15' and the other with the guide 16'. By rotating the pinion, movements in opposite directions are imparted to the guides, which movements may be faster than those obtained with the screw having threads of opposite pitch as described previously.

The rubber tube 27 which so to speak forms the body or barrel of the pump, and on which the push-rods 17 and 18 act in the manner of check-valves, is clamped for the purpose of discharging the fluid contained therein, between the movable plate 19 and the fixed abutment plate 28, as stated above. The abutment plate 28 remains stationary throughout the operation of the apparatus, but may be mounted so as to be adjustable and also to be foldable as will now be explained.

Adjustment of the plate 28 makes it possible to adapt the device for use with rubber tubes of various gauges or thicknesses. Such adjustment is obtained by means of the following device.

The plate 28 is through the medium of a pin 29 mounted on two supports 30 and 30' which are freely slidable on the base 1, said supports being guided by the side edges of the ports 1' which are engaged by the extensions 30'' of the supports 30 and 30'. Said extensions are formed as forks into which project levers 35 and 35' rigid with the shaft 36, rotatable on pins 31 and 31' rigid with the base 1, as best shown in Figs. 2 and 3. A lever 38 is rigid with the shaft 36 and said lever is engaged by a set-screw 39, which screw may be actuated by means of an adjusting knob 40 and is threaded into the side wall of the base 1. The supports 30 and 30' are maintained in place on the base frame 1 by means of strap members 41 and 41' with which they are made rigid through screws 42 or any suitable equivalent means.

It will be readily understood that when the screw 39 is actuated the assembly comprising the

supports 30 and 30' and the abutment plate 28, may be advanced or retracted and consequently the push-rods 15 and 16 may be made to sufficiently flatten down the tube 27 to obturate it without however crushing it to the point of injury, whatever the thickness of said tube may be.

Moreover, the abutment plate 28 may be completely folded back to enable removal or insertion of the rubber tube 27. For that purpose said plate may be rotated about the axis 29 to assume the position indicated at the left of Fig. 1. As shown in this figure, the supports 30 and 30' are formed with notches 30'', thereby enabling the tube 27 to be inserted (or removed) when the abutment plate 28 is in folded back condition. As a result of this arrangement, positioning and removal of the tube may be effected without even having to look at it and possibly in complete darkness.

The abutment plate 28 is maintained in its operative position (as shown at the right of Fig. 1) by two latches 32 and 32' (see in particular Fig. 5) engaging recesses 31 and 31' formed in the supports 30 and 30'; a spring 33 urges the latches into their recesses; actuating lugs 34 and 34' formed at the ends of the latches allow them to be extracted from out of their recesses by compressing the spring 33 when it is desired to clear the abutment 28 in order to remove or insert a tube 27. When the latches engage their recesses, they are effective to block the abutment plate 28 in the position to which it has been brought in the above-described adjustment and they enable it to withstand the pressure exerted by the tube 27 when the latter has been compressed by the push-rods 17, 18 and the pressure plate 19.

It is important that the operator have a correct knowledge of the amount by which the rate of flow through any given tube is altered when the set screw 28 causing longitudinal displacement of the guides 15' and 16' and thereby the push-rods 15 and 16 together with the plate 19, is actuated. This result is obtained by means of an indicating device (Fig. 18) comprising an indicator arm or needle 46 movable in front of a graduated scale on a dial. If said indicator arm were displaced proportionally with the amplitude of displacement of the guides 15' and 16' it would be necessary to provide a non-uniform spacing between the scale-graduations of the dial, since the rate of flow through a cylindrical tube is not varied in a directly proportional manner in response to the degree of flattening to which it is subjected by being clamped against a planar surface. To overcome these drawbacks a correcting device is provided which comprises a cam 43 mounted on the wall of the base 1 by means of a pin 44 on which it is freely rotatable; said cam is engaged by a finger 45 rigid with any one of the guides 15' or 16'. It will easily be understood that the contour of the cam 43 may be so calculated that the indicating arm 46 will be caused to travel through equi-spaced scale graduations even though the corresponding length of stroke of the cam controlling guide may have been subjected to irregular variations.

It goes without saying that without altering the basic organization of the invention, it would be possible to actuate through the medium of a gearing or a gear train controlled from the cam 43, a second indicator arm serving to indicate a fraction of the main scale graduations. Also two cams could be used each controlled from one of the guides 15' and 16' so as to make it possible to ascertain without requiring any calculations,

the rate of flow for a predetermined adjustment through two tubes of different diameters.

The device moreover comprises a flow registering and totalizing device adapted to automatically compensate for any deviations in the rate of flow such as may be caused by the displacement of the guides 15' and 16'. Said device is essentially formed by a counter 47 of any suitable type controlled by a lever 48 adapted to transmit to it the impulses received from a toothed ratchet 49 adapted to rotate the drum of the counter by an amount equivalent to one digit per tooth.

The ratchet 49 is driven through a mechanical connection formed by a spring 50 having juxtaposed turns wound around a cylinder 51 rigid with the ratchet 49, and one end of which is blocked by means of a screw 52' on a lever 52 in such a way that each impulse of the lever 52 which tends to tighten the spring 50 around the cylinder 51 causes the latter to be rotated, while in the reverse movement, tending to unwind or release the spring 50, the latter may rotate freely around the cylinder 51 without driving the latter.

25 A second spring 53 wound in an opposite direction around the cylinder 51 and one end of which is blocked on the frame 54 of the driving device with a screw 54', allows the ratchet 49 to be rotated freely when urged by the spring 50, but effectively blocks the ratchet when the spring 50 is moved in the reverse direction.

A link 25 connects the lever 52 on which it acts through the medium of a pin 55, with a lever 26 to which it is fixed by a pin 56; the lever 26 is 35 pivoted on the base 1 by means of a pin 26' and receives the impulses from the guide rod 22 formed for that purpose (as previously stated) with an aperture 24' into which extends the free end of the lever 26. A return spring 24'' (Figs. 40 13 and 14) rigid at one of its ends with the lever 52 and at its opposite end with a ratchet wheel 57 adapted to be blocked by means of a pawl 58 pressed by a spring 58' and rotatable on the pin 59 rigid with the frame 54, retracts the lever 52 after each impulse received from the plate 19 through the guide rod 24 from the lever 26 and the link 25; said spring at the same time retracts the plate 19 against the push-rods 15 and 16, which in turn act upon the levers 1-1' and 8-8' to apply them against the cams 3 and 4.

50 The ratchet wheel 57 which is rotatable on the pin 60 carried by the frame 54 enables adjustment of the tension of the return spring 24''.

As explained in greater detail hereinafter, the above described counter functions as a totalizer for fractions of a digit.

The frame 54 (which supports the ratchet 57 and related elements) and the counter 47 are secured on the casing 61 supporting the base 1 and serving to house an electric motor 62 controlling the device.

The motor 62 has been especially devised for use in connection with my apparatus as used for medicinal purposes. This specific application of the device requires an arrangement such as to 65 positively preclude the possibility of any contact at any time between the oil necessary to lubricate the motor and the members through which the liquids or gases to be injected are circulated. This result is obtained according to the invention through the use of an oil chamber 63 devised so as to produce the lubrication of a train of gears without necessitating renewal or replenishing of the lubricant. To that end, a sufficiently large amount of the latter is contained in the lower part of the motor casing which forms a

sump or chamber 63 the shape of which is determined so that the oil level may at no time reach the bearing for the motor drive shaft, which bearing seals said chamber, and this being true for any position of the motor. In other words, the apparatus may be turned upside down, or placed on its side, or generally may be made to assume any position whatever without the possibility of any oil escaping through the bearing, said chamber being moreover completely oil-tight everywhere else.

In order to prevent the oil from rising in the motor under the effect of air pressure, resulting from the heat evolved in the motor in operation, there is provided a tube through which the motor chamber is vented to the atmosphere; said tube is arranged in such a way that the level of oil can never reach its inlet in the chamber.

Said special motor is also characterized by an arrangement ensuring a particularly efficacious guiding of its shaft. As shown in Fig. 1, the drive shaft proper 65 driven from the rotor 64 is a tubular shaft; it is supported in a lower bearing 66 and guided in an upper bearing 67. Said shaft has secured thereon a pinion 68 which engages one or more pinions 69 rigid with pinions 70 which in turn drive a pinion 71 rigid with a shaft 72 rotatable within the tubular shaft 65. Said shaft 72 rests on a thrust bearing 73; it is guided throughout its entire length and drives the shaft 2 carrying the control cams.

In a modification of the device, the connection between the shaft 72 and the shaft 2 is effected through a free-wheel arrangement allowing the shaft 2 to be rotated by hand without driving the motor.

In the above the control of only one tube 27 has been described; the apparatus illustrated is provided with two tubes, and, as stated above, the mechanism described is simply duplicated, with the exception of the motor and the shaft 2, which in this case supports a second set of cams.

The pump may be operated to suck and discharge synchronously or alternately through both tubes (in the latter case one tube effects aspiration while the other one discharges). This result may be obtained very simply by means of the device now to be described and more particularly illustrated in Figs. 8 and 9.

In order to modify the manner of operation of the pump, it is simply necessary to change the setting of the second set or trains of cams 3', 4', 5', 6' designated by the general reference 74 in Fig. 8. For that purpose, said set of cams is driven by means of a retractable key 75 accommodated in a chamber 75' formed in the thickness of the shaft 2 and subjected to the action of two springs 76 and 76' which urge it into engagement, according to requirements, in either one of two grooves 77 or 77' formed in the thickness of the set of cams.

The previously mentioned cams 3, 4, 5 and 6 form a first set or train rigid with the shaft 2; the second set of cams 74 may, with respect to said first train, be so adjusted that the action of both tubes may be synchronized or on the other hand alternated. To modify the setting of the train of cams 74, there are provided flats 78, 78' extending perpendicular to each of the grooves 77 and 77' as shown in Fig. 9, said flats making it possible to expose said grooves while being in tangential relation with the inner diameter of the bush in which the shaft 2 is rotatable. A push-rod 79 formed by a plate bent

in the form of a U (Figs. 8 and 9) is arranged to extend between each pair of cams of the train 74 so that it may, when caused to slide in its housing formed in the post 23, engage the retractable key 75 to expel it from out of that one of the grooves in which it is engaged. A spring 80 restores the push-rod 79 to its rest position when no longer compressed.

It will readily be understood that if the push-rod 79 is pressed while the shaft 2 is rotated, the ends of the push-rod will, at the instant where the flat is presented before them, engage the key 75 and will expel it from out of the groove in the train of cams 74; the latter will then no longer be driven through the key 75 and will stop, since the push-rod, through the pressure exerted by it on the flat, will immobilize said set of cams, the shaft 2 still remaining freely rotatable. In this rotation of the shaft 2, the key 75 will encounter the groove which was free and will at once project thereinto, whereby the train of cams 74 will once more be rigid with the shaft 2 and the drive of said set of cams will once more be effective. At the same time, the push-rod 79 is expelled by the action of the flat applied against it and acting as a cam.

The result of this operation is that the setting of the train of cams 74 will have been altered with respect to that of the train formed by the cams 3, 4, 5 and 6. This alteration in the setting will obviously be obtained each time that the push-rod 79 is pressed during the rotation of the shaft 2.

The shaft 2 may be extended beyond the upper plate of the frame 1 to receive a crank thereon, enabling the device to be operated manually in case of a power breakdown. Also a pulley (or a pinion) may be adapted thereon to serve for the drive of an accessory device through a drive belt or chain.

The operation of the apparatus as described is as follows:

The abutment 28 being swung back, the rubber tube 27 is brought opposite to the push-rods 17, 18 and to the pressure plate 19 by causing it to rest in the notches 36'' in the supports 30 and 30' which maintain it in proper position (see Fig. 1). The abutment 28 is then raised and blocked on the supports 30 and 30' by means of the latches 32 and 32'. If necessary the abutment 28 is then adjusted. For that purpose the screw 39 is unscrewed and the end of the tube corresponding to the intake side is dipped into a suitable liquid; the apparatus is then started and the screw is tightened until the liquid is aspirated and discharged by the tube. The apparatus is then in adjusted condition. Aspiration and discharge are caused by the associated action of the pressure-plate 19 and the push-rods 17 and 18. Since the apparatus is reversible, the intake may be effected at will through either end of the tube. It will be assumed for example that the left hand end of the tube (as seen in Fig. 5) is used for intake: In this case, the device operates as follows:

The push-rod 17 having been actuated by operation of the cam 5 and levers 9 and 9', until it has completely obstructed or throttled the tube 27, the plate 19 which was pressing the tube after it had flattened it out, is retracted by the action of the return spring 24' which pushes back the levers 7 and 8 against the cams 3 and 4. In this movement, the push-rod 18 is brought completely clear of the tube. In such conditions, the liquid or gas to be aspirated penetrates into

the tube under the effect of the suction produced by the straightening out of the walls of the tube. When the plate 19 has been completely retracted and consequently the suction effect has reached its maximum value, the push-rod 18 is brought to the position causing throttling of the tube, while the push-rod 17 on the other hand is retracted. At the same time, the plate 19 is caused to clamp the tube 27 against the abutment plate 28, thereby causing discharge of the fluid by compression of the tube. This intake and discharge cycle is repeated as long as the device is in operation.

If the direction of rotation of the cams is reversed, the flow of fluid in the tube is also reversed.

The rate of flow may be adjusted by means of the screw 20 with opposite screw threads which is adapted to bring the push-rods 15 and 16 closer to or further away from the pivotal axis of the levers 1' and 8'; the amplitude of stroke of said push-rods (and therefor that of the clamping plate 19) is thus altered. It will be easily understood that the more closely spaced are the push-rods with respect to the ends of the levers, the larger will be the amplitude of the movements of the plates 19; conversely, as said push-rods are brought closer to the fulcrum axes of the levers, said amplitude will be decreased until it becomes zero as the push-rods pass exactly through the axis of the levers.

The variation of the stroke of the plate 19 is effective to produce a more or less pronounced collapse of the tube and consequently to alter the rate of flow.

It is obvious that this method of adjustment is such that the rate of flow in each tube is independent from the rate of rotation of the cams. This makes it possible to adjust once for all said rate of rotation and thereby makes it possible to use a synchronous motor permitting a strictly stable rate of rotation and consequently a uniform rate of flow, which is particularly valuable and desirable in medicinal use.

As indicated in the course of the disclosure, the apparatus may be adapted to act on any desired number of tubes; when two tubes are used, it may be desirable to synchronize their deliveries or on the other hand to cause them to alternate. This possibility makes it possible, without modifying the rate of rotation of the motor, to double the frequency of the pumping action. Thus, for instance, if the apparatus is established to provide eighty aspirating and delivery cycles per minute for each tube, both tubes operating alternately, the total frequency will be brought up to 160 pulsations per minute or may be reduced to 80 if the tubes are operated synchronously, that is if they aspirate and deliver at the same times.

In order to alter the frequency, or in other words to synchronize the action of the mechanism in both tubes, or on the other hand to cause such action to alternate in both tubes, it is simply necessary, the apparatus being in operation, to press on the push-rod 19 to automatically produce in the above-indicated manner a change in the relative setting of both trains of cams. At each push exerted on the push-rod 19, there will be produced a different combination in the control of the levers acting on said tubes.

The flow indicator shown in Fig. 18, for a given gauge of tubing, allows the apparatus to be adjusted so as to deliver any desired volume of liquid or gas. If it becomes necessary to use a

tube of a different gauge from that for which the scale graduation of the dial was designed, there would be accomplished, for the subsequent adjustment of flow, a calibrating operation which will make it possible to calculate the rate of flow once the corresponding value of each scale graduation for said tube is ascertained.

It is also possible, by replacing a cam 43 by another cam of a predetermined contour, to adapt the flow indicator to tubes of various characteristics.

The previously described registering counter is adapted to automatically correct any errors which may result from the fact that the rate of flow of the tube is varied with the displacement of the push-rods 15 and 16 along the levers 1' and 8'. The counter in question is adapted to register the number of strokes or cycles performed by the plate 19. But, since those strokes are not all of the same length it is important that the counter should register one additional digit only when the sum of several strokes of the plate 19 has given rise to the delivery through the tube 27 of a predetermined amount, for instance 1 cc. Such result is obtained by the action of the compensating device which operates as follows: The lever 26 transmits to the lever 52 through the medium of the link 25, the impulses received from the plate 19; in turn the lever 52 drives the ratchet 49 through the agency of the spring 50. As previously described, for one direction of movement of the lever 52, the spring is blocked on the cylinder 51 and is effective to drive it, while in the opposite direction, it releases said cylinder which is then blocked by the spring 53. Each time the ratchet 49 has advanced by the amount of one tooth, the lever 48 which transmits the movement to the counter 47 through a link 48' causes one step of advance of the units drum of the counter and the latter then totalizes the number of impulses. But, when the pump is adjusted, in such a manner that a certain number of strokes of the plate 19 is required to produce the delivery of one unit of volume (1 cc. for example), the gear of the counter only advances, at each impulse received from the lever 26, by an amount corresponding to the amplitude of the movement of said lever (the lever 26 remaining stationary in the limiting case where the plate 19 is adjusted for a rate of flow through the tube equal to zero); each stroke of the plate 19 of an amplitude smaller than that which would cause the delivery of one unit volume, feed the ratchet 49 by a fraction of a tooth space and said ratchet 55 remains in such position until a new stroke of the plate 19 causes it to be fed by a new fraction. When the total of elementary impulses thus imparted to the ratchet 49 amounts to one unit, said ratchet is advanced by one tooth and causes the 60 indication of an additional unit in the drums of the counter.

In a modification of the invention, the tube of uniform gauge described above is replaced by a tube comprising, in the portion thereof forming the pump barrel, a resilient bulb on which the pressure producing delivery is adapted to be exerted; in this case, said bulb should be actuated on both sides thereof, and simultaneously the plate 19 and the abutment 28 should be controlled.

What I claim is:

1. In a device for pumping medicinal fluids in combination a flat abutment surface adapted to fixedly removably receive a length of flexible tubing thereagainst, a movable guided pressure-plate 75 adapted to be moved towards and away from said

11

abutment surface, a spring-urged push-rod co-operating with said abutment surface beyond each end of said pressure-plate to throttle a related point of said tube thereagainst, a cam-shaft with suitably settable cams thereon, means to rotate said cam-shaft, for each of said push-rods a follower lever, means co-operating with one of said cams to control said push-rod, a pair of levers each having a fixed fulcrum and provided with a follower arm and an actuating arm, said follower arm co-operating with a related cam, two movable projections on said pressure-plate each co-operating with a related one of said actuating arms and adjustably movable on said pressure-plate in relation to said fulcrum of said last-mentioned levers to cause said pressure-plate to be actuated to a variable degree towards said abutment surface, flow-indicator means including a scale graduation and an indicator arm operatively connected to said movable projections on said pressure-plate to indicate the degree of adjustment thereof with respect to the fulcrum points of said last-mentioned levers whereby to be responsive to the degree of actuation of said pressure-plate, said operative connection including a cam device of suitable profile whereby the displacements of said indicator arm on said scale may be made to be proportional with the actual rates of flow through said tube for the various degrees of actuation of said pressure-plate, the setting of said cams being such as to produce a suitable sequence of operation of said pressure-plate and said push-rods to effectively pump fluid through said tube.

2. In a device for pumping medicinal fluids in combination a flat abutment surface adapted to fixedly receive a length of flexible tubing thereon, a reciprocable pressure-plate adapted to be reciprocated towards and away from said pressure-plate, means to adjust the amplitude of said reciprocation, spring-urged push-rods co-operating with said abutment surface beyond each end of said pressure-plate to throttle a related point of said tube thereagainst, a cam-shaft with suitably settable cams thereon, an electric motor to drive said cam-shaft at a constant rate, means to control said pressure-plate and each one of said push-rods from a respective one of said cams, the setting of said cams being such as to cause a predetermined pumping sequence of operations of said pressure-plate and said push-rods to pump fluid through said tube, a counting and totalizing means to register the total amount of fluid pumped through said tube, said means comprising a registering wheel, a ratchet adapted when and only when advanced by the space of one tooth to advance said registering wheel by one digit, and means to cause each actuation of said pressure-plate with respect to said abutment surface to cause a corresponding advance of said ratchet, the arrangement being such that said ratchet is caused to be advanced by the amount of one tooth thereof for a number of actuations of said pressure-plate corresponding to the passing of one unit volume of fluid through said tube.

3. In a device for pumping medicinal fluid and the like in combination a flat abutment surface adapted to fixedly receive thereon a length of resiliently flexible tubing connecting with a supply of fluid to be pumped and with a means for utilizing said fluid, a reciprocable pressure-plate adapted to be variably reciprocated towards and away from said abutment surface to variably throttle said length of tubing, means to adjust

75

12

the amplitude of reciprocation of said plate and thereby the degree of throttling of said tube and means to indicate said adjusted amplitude and thereby the amount of fluid flow through said tube at each actuation of said pressure-plate, spring-urged push-rods co-operating with said abutment surface beyond each end of said pressure-plate to completely throttle off a related point of said tube, a cam-shaft with suitably settable cams thereon, control means from each of said cams to said pressure-plate and each of said push-rods respectively to operate the same in a pre-determined pumping sequence as determined by the setting of said cams, an electric motor, a sealed housing for said motor, the lower part of said housing forming an oil sump, gearing connections from said motor to said cam-shaft operating in said oil sump, the arrangement being such as to prevent any escape of said oil from said sump for any position of said device.

4. In the device as claimed in claim 3, means for venting of said sump to atmosphere to prevent a rise of oil therein under the effect of pressure of air heated by the operation of the motor.

5. In a device for pumping medicinal fluids and the like in combination two flexible tubes with resiliently collapsible side-walls each connected with a respective supply of fluid to be pumped on one hand and a means for utilizing said fluid on the other hand, means for removably supporting a length of each of said tubes against a flat abutment surface, for each of said tubes a pressure-plate adapted to be variably reciprocated towards and away from said abutment surface to variably throttle said tube thereagainst, means to adjust the degree of reciprocation of said pressure-plate and means to indicate the degree of said reciprocation and consequently the amount of each fluid flowing through each of said tubes at each reciprocation of said pressure-plate, spring-urged push-rods co-operating with said abutment surfaces beyond each end of said pressure-plate to completely throttle a related point of each of said tubes thereat, a common cam-shaft with two series of cams thereon one for each tube, a motor to drive said cam-shaft, control means for one of said cams of each series to a respective pressure-plate and from cams of each of said series to related push-rods of a respective tube, means for setting each of said series of cams so as to cause a suitable pumping sequence of operations of the related pressure-plate and push-rods to pump said related fluid from said supply to said utilization means through said related tube, and means for altering the relative setting of both said series of cams with respect to each other while said cam-shaft is in rotation, so as to selectively obtain a relative timing such that said pressure-plates and push-rods for both tubes are operated in unison to simultaneously deliver their respective fluids through said tubes, or alternatively to obtain a relative timing such that the respective fluids are delivered alternately through both tubes.

6. The device as in claim 5, wherein said means for selectively altering the relative setting between both said series of cams comprises a pair of angularly spaced longitudinal grooves in said cam-shaft opposite to one of said series of cams, a retractable key adapted to engage any one of said grooves selectively to cause said series of cams as a whole to be coupled with said cam-shaft in a related one of two angular settings with respect to the other series of cams, and

means for retracting said key while said shaft is in rotation to allow said setting to be automatically altered.

7. In a device for pumping medicinal fluids and the like in combination a supporting frame, two flexible tubes each connectable with a respective supply of fluid on one hand and with means for utilizing said fluid on the other hand, means for removably supporting a length of each of said tubes horizontally at each side of said supporting frame, an abutment member for each of said lengths of tubes latching in an operative vertical position to engage a generatrix of said tube and pivotable to an inoperative horizontal position to enable the removal and insertion of said tube, for each of said tubes a reciprocable pressure-plate adapted to be variably horizontally reciprocated towards and away from said abutment plate to variably throttle said length of tube thereagainst, means to adjust the degree of reciprocation of said pressure-plates, and means to indicate said adjusted degree of reciprocation calibrated in units of volume flow per unit of time, spring-urged push-rods co-operating with said abutment plates beyond each end of said pressure plates to completely throttle a related point of said tube thereat, a common vertical camshaft rotatably mounted centrally of said frame with two series of cams thereon one for each tube, control means from the respective cams in each series to the pressure plate and the push-rods of a related tube, means for setting each of said series of cams to cause a suitable pumping sequence of operations of said pressure-plates and said push-rods for each tube, and means for altering the relative setting between both said series of cams while said camshaft is in rotation so as to obtain selectively a simultaneous or an alternating delivery of fluid through both tubes, totalizing counter means for registering the amount of fluid flow through each tube, a synchronous electric motor housed under said supporting frame in a casing, an oil sump formed in the bottom of said casing containing a substantial amount of oil therein, bearings in said casing for the driveshaft of said motor, and means to positively prevent said oil from leaking through said bearings into said supporting frame.

8. The pumping device as in claim 7, wherein said drive-shaft of said motor is a tubular shaft co-axially surrounding said camshaft and adapted to drive the latter through a train of gears arranged to work in said oil-sump.

9. In a device for pumping fluids in combination a fixed abutment surface adapted to fixedly removably receive a length of flexible tubing thereagainst, one end of said tubing communicating with a source of fluid to be pumped and the opposite end with a means for utilizing said fluid, a reciprocable pressure-plate to be moved towards and away from said abutment surface, guiding means for said pressure-plate, first push-rods each having an end engaging said pressure-plate, second push rods each cooperating with said abutment surface beyond each end of said pressure-plate adapted when actuated to flatten out and throttle a related point of said tube against said abutment surface, guiding means for said first and second push-rods, spring means for urging said first and second push-rods away from said abutment surface, a rotatable camshaft, settable cams on said camshaft, follower levers cooperating with each one of said cams, pins associated with and secured to a related one of said levers respectively, actuating levers fixed on each of said pins and each cooperating with a related one of said push-rods, and means for displacing said first push-rods in reverse directions with respect to each other substantially along the related ones of said actuating levers thereby causing said pressure-plate to be moved to a variable extent from said pins through said actuating levers according to the adjustment of said first push-rods with respect to their associated actuating levers, the setting of said cams being such as to provide for a predetermined pumping sequence of operation of said pressure-plate and said second push-rods to cause pumping of said fluid from said source to said utilization means, and a constant speed driving mechanism for operating said camshaft.

HENRY, LOUIS JOSEPH.
